TOILET BOWL BRUSH HOLDER

James C. Fry, Wooster, Ohio, assignor to Rubbermaid
Sales Corp., Wooster, Ohio

Filed Aug. 9, 1972, Ser. No. 278,934

Term of patent 14 years

Int. Cl. D7—99

U.S. Cl. D6—85

FIG. 1

FIG. 2

FIG. 3

FIG. 4

FIG. 5

FIG. 1 is a front elevation of a toilet bowl brush holder embodying my new design.

FIG. 2 is a side elevation thereof.

FIG. 3 is a vertical sectional view showing the holder in open position.

FIG. 4 is a cross-sectional view on line 4—4 of FIG. 2.

FIG. 5 is an exploded perspective view.

I claim:

The ornamental design for a toilet bowl brush holder, as shown.
